ADJUSTABLE NOZZLE

Michael S. Gallick, Binghamton, N. Y., assignor
to General Aniline & Film Corporation, New
York, N. Y., a corporation of Delaware

Application April 16, 1949, Serial No. 87,858

6 Claims. (Cl. 299—149)

1

This invention relates to nozzles or jets for blowing a stream of gaseous medium, and more particularly to air nozzles for applying a blast of air of oblong shape and uniform cross-section.

Air nozzles of this character, often referred to as "air knives," are employed in coating operations where a moving web is coated with a solution and the excess coating composition is removed with an air stream directed at a suitable pressure against the coated side of the web. The air, or in some cases certain gases, is expelled through an elongated aperture of the nozzle whereby the air or gas is delivered in an oblong shape such as a substantially flat thin sheet running transversely to the direction of travel of the web.

In existing types of air nozzles the nozzle consists of a plenum chamber, to which are attached two elongated lips either or both of which are so constructed that the distance separating them at the point of issuance of the air stream is adjustable. In theory, the air pressure in the plenum chamber, and with it, the velocity of the air stream issuing from the air nozzle, varies inversely as the distance separating the two nozzles at the point of issuance of the air stream. The velocity of the air stream, in turn, determines the amount of excess coating composition which is removed, or, conversely, the amount of desired coating composition which is left on the web, and controlling the velocity of this stream of air is the most convenient and accurate means of controlling the amount of coating composition left on the web.

However, in nozzle constructions, the means utilized heretofore for controlling or adjusting the separation of the two nozzles at the point of issuance of the air stream is so cumbersome and difficult to adjust that this adjustment is rarely used. In prior devices the adjusting means generally consist of a multiplicity of threaded bolts, more or less closely spaced across the width of the air nozzle, and so arranged that turning any one bolt will open or close the nozzle spacing in the area of the nozzle controlled by that particular screw. Consequently, in order to either open or close the overall nozzle opening, so as to control the effective air pressure, all of the adjusting screws must be turned.

The above described construction is useful only to correct the inevitable inaccuracies in parallelism of the two lips constituting the air nozzle, introduced either during construction or by accidental damage subsequent thereto. These inaccuracies are overcome by warping one, or both, of the two lips by suitable adjustments of the

2

aforesaid adjustment bolts, so as to establish substantial parallelism of the two nozzles, at least at the point of issuance of the air stream. The fact that all adjustments to the nozzle opening must simultaneously include adjustments to compensate for lack of parallelism as previously explained contributes materially to the disuse of adjustment of the air nozzle opening as an overall control of air pressure in the operation of air jet, or air knife, coaters.

The primary object of this invention is to improve upon the construction of nozzles or air knives and thereby eliminate the above enumerated disadvantages.

Another object of the invention is to provide a nozzle construction which will permit a simple overall adjustment of the effective width of the nozzle opening.

A further object of the invention is to provide a nozzle construction in which, aside from the overall adjustment of the nozzle opening, individual adjustments of particular areas thereof may be effected independently from the overall adjustment.

Another object of the invention is to maintain parallelism between the knife edges determining the effective width of the air stream over the entire range of overall adjustment.

Other objects and advantages will be apparent from the following description of the invention, defined in particularity in the appended claims, and taken in connection with the accompanying drawing, in which:

Figure 1 is a sectional view of the nozzle in accordance with the invention showing the overall adjustment means.

Figure 2 is a perspective view of the nozzle; and

Figure 3 is an exploded view of a portion thereof showing one of the supports of the knife-edged blade and its incremental adjustment.

By constructing the air nozzle in accordance with this invention in such a manner as to provide separate adjustment for the overall spacing between the knife edges determining the nozzle opening, and independent adjustments for the control of parallelism of the knife edges over the entire length, the use of the nozzle is greatly facilitated resulting in flexibility and ease of operation. In addition, adjustments to correct for the lack of parallelism of the knife blades independent from their overall spacing, distributed at close intervals affords easy correction for either inaccuracies in manufacture or accidental damage which would disturb the desired parallel relationship.

Referring to the drawings, in Figures 1 and 2

the nozzle construction includes a plenum chamber defined by a cylindrical side wall 4 closed at both ends by covers 5 and 5' having air intake ducts 6 and 6', respectively. An upper blade 8 and a lower blade 8', both having complementary knife edges, are slidably mounted at a predetermined angle to one another in a plurality of complementary guides 9 and supports 10. In the embodiment shown, the guides are machined into the blades and the supports are held on the wall of the plenum chamber by means of eccentric bolts 11.

Blades 8 and 8' are connected to a yoke 13 by means of pull bars 14 and 15 through links 16 and 17. A threaded shaft 18 engages at one end the threaded portion of the yoke 13. The other end of the shaft extends outside the chamber and carries a knurled knob 19 for manual adjustment. Rotation of the knob 19 causes the yoke 13 to move parallel to a line drawn through the axis of the shaft 18 and continued through the points of juncture of blades 8 and 8'. This movement is transmitted to the blades and causes them to move at a predetermined angle to each other and to the above axis, thus increasing or decreasing the spacing between the knife edges at points of juncture. A sealing washer 20 is used to eliminate air leakage on the shaft 18 and sealing strips 21 and 22 serve a similar function between the engaging surface of the blades 8 and 8' and the inturned edge of the wall 4 of the chamber.

The above described linkage operated by the knob 19 may be installed singly in the center of the nozzle assembly, but it is preferred to use two duplicate linkage systems installed near the opposite ends. For long assemblies, a plurality of equidistantly placed linkage systems are preferred from a practical standpoint. Where multiplicity of linkages are used, each linkage system may be separately controlled by its associate knob, or the latter may be replaced by sprockets, pulleys or gears, and each linkage system interconnected by means of chains, cables or a gear train so as to operate in unison from a single control.

The individual adjustments for maintaining parallel relationship between the blades may better be understood by reference to Figure 3. As previously mentioned, the guides 9 are machined into the blades, and the supports in the form of T-shaped arms are fixed to the wall 4 of the chamber. Each arm has a horizontal portion which slides in the guide 9 and a vertical portion which fits in a slot 12 machined into the wall 4. The vertical portion is provided with a transversely elongated aperture through which the fastening bolt 11 may be inserted, the latter having a threaded portion which engages a suitable female thread in the slotted part of the wall 4. Lock washer 23 between the head of the bolt 11 and the horizontal portion of the arm 10 is used to tension the bolt, thereby holding the assembly securely together. Enough thread is provided on the eccentric shank of the bolt to allow rotation over a portion of a turn to make use of the leverage action of the eccentric shank in connection with the elongated aperture in the vertical portion of the arm 10. In this manner, rotation of the bolt 11 will cause the arm 10 to move tangentially to the circumference and at right angles to the longitudinal axis of the chamber. A half-turn of the respective bolt will give the necessary compensating displacement to bring either the blade 8 or

8' into parallel relationship in the vicinity where the particular support engages the blade. The lock washer 23 is under tension at all times, and thus prevents turning of the bolt under the influence of vibration.

The adjustment for compensating small differences in the parallel relationship of the knife-edged blades is subject to the resiliency of the blades and bending in either direction is within allowable elastic limits. The overall adjustment of the distance between the blades is independent from the compensating adjustments so that compensation is maintained over the entire range of spacing between the blades. After differences in parallel relationship of the blades are corrected by the adjustments provided, this relationship will be maintained for all positions of the blades controlled by the overall adjustment shown. The air pressure may then be regulated easily and simply by the overall adjustment.

I claim:

1. An adjustable nozzle for blowing a stream of gaseous medium in an oblong shape and variable cross section comprising an elongated closed chamber, an intake therefore, a pair of juxtaposed longitudinally extending blades in the wall of said chamber defining an opening, means for moving said blades in the direction transverse to the longitudinal axis of said chamber thereby to adjust the overall width of the stream forced through said opening, and means for adjusting at points distributed along the longitudinal axis of said chamber the effective parallel spacing between portions of said blades throughout said adjustment of overall widths.

2. An adjustable nozzle for blowing a stream of gaseous medium in an oblong shape and variable cross section comprising an elongated closed chamber, an intake therefore, a pair of juxtaposed longitudinally extending blades in the wall of said chamber defining an opening, means for moving said blades in the direction transverse to the longitudinal axis of said chamber thereby to adjust the overall width of the stream forced through said opening, and means, independent from said overall adjustment, for adjusting at points distributed along the longitudinal axis of said chamber the effective parallel spacing between portions of said blades, said parallel spacing being maintained throughout said adjustment of overall widths.

3. An adjustable nozzle for blowing a stream of gaseous medium in an oblong shape and variable cross section comprising an elongated closed chamber, an intake therefore, a pair of juxtaposed longitudinally extending blades having facing edges parallel to each other in the wall of said chamber defining an opening, means for moving said blades in the direction transverse to the longitudinal axis of said chamber thereby to adjust the overall width of the stream forced through between said edges, and eccentric means for adjusting at points distributed along the longitudinal axis of said chamber the effective spacing between portions of said edges whereby substantially parallel relationship is maintained between the edges over the length of said blades.

4. An adjustable air nozzle for blowing an air stream in an oblong shape and variable width comprising a plenum chamber of elongated construction having a side wall and closed ends, an air intake connecting with the interior of said chamber, an air exhaust including a pair of longitudinally extending blades having juxtaposed

knife edges, a plurality of supports for said blades along the side wall of said chamber, means for sliding said blades inwardly at an angle transversely to the longitudinal axis of said chamber whereby said blades may be separated, the distance between said edges determining the width of said air stream, a manual adjustment outside said chamber for affecting said sliding movement and individual adjustments at said supports for incremental variation of said distance at areas near each of said supports.

5. An adjustable air nozzle for blowing an air stream in an oblong shape and variable width comprising a plenum chamber of elongated construction having a side wall and closed ends provided with an air intake, an air exhaust including a pair of longitudinally extending blades having juxtaposed knife edges, a plurality of supports for said blades along the side wall of said chamber each comprising a T-shaped arm having a vertical and horizontal portion, guides in said blades accommodating said horizontal portions and guides in said wall for slidably accommodating said vertical portions; means for sliding said blades over said horizontal portions inwardly at an angle transversely to the longitudinal axis of said chamber whereby said blades may be separated, the distance between said edges determining the width of said air stream; individual adjustments at said supports for maintaining parallelism of said knife edges for incremental variation of said distance at areas near each of said supports comprising a bolt having an eccentric shank securing said vertical portions to the side wall of the chamber, said shank being rotatable within a transversely elongated aperture in said arm whereby turning any one of said bolts forces said arm to slide in said wall guide and constrain a portion of said blade in the desired direction.

6. An adjustable air nozzle for blowing an air stream in an oblong shape and variable width

comprising a plenum chamber of elongated construction having a side wall and closed ends provided with an air intake, an air exhaust including a pair of longitudinally extending blades having juxtaposed knife edges, a plurality of supports for said blades along the side wall of said chamber each comprising a T-shaped arm having a vertical and a horizontal portion, guides in said blades accommodating said horizontal portions and guides in said wall for slidably accommodating said vertical portions, means for sliding said blades over said horizontal portions inwardly at an angle transversely to the longitudinal axis of said chamber whereby said blades may be separated, the distance between said edges determining the width of said air stream, comprising pull bars linked with said blades within said chamber, a yoke interconnecting said pull bars, a thread in said wall engaging one end of a shaft, the other end extending from said chamber and a handwheel affixed to said other end; individual adjustments at said supports for maintaining parallelism of said knife edges comprising a bolt having an eccentric shank securing said vertical portions to the side wall of the chamber, said shank being rotatable within a transversely elongated aperture in said arm whereby turning any one of said bolts forces said arm to slide in said wall guide and constrain a portion of said blade in the desired direction.
